RESILIENT SEALING STRIP FOR WEATHERSTRIP ASSEMBLIES

Alfred P. McEvoy and Tym F. Seay, Dallas, Tex.

Application August 5, 1957, Serial No. 47,215

Term of patent 14 years

(Cl. D13—6)

Fig. 1

Fig. 2

Fig. 3

Fig. 4

Figure 1 is a perspective view of a resilient sealing strip for weatherstrip assemblies, showing our new design. The strip is shown broken away to represent indeterminate length.

Figure 2 is an enlarged end view thereof;

Figure 3 is a fragmentary top plan view of the strip; and

Figure 4 is a fragmentary bottom view thereof.

We claim:

The ornamental design for a resilient sealing strip for weatherstrip assemblies, substantially as shown.
